UNITED STATES PATENT OFFICE.

LOUIS J. DEASY, OF CINCINNATI, OHIO.

TROLLEY-POLE.

1,115,789.

Specification of Letters Patent. Patented Nov. 3, 1914.

Application filed June 13, 1914. Serial No. 844,978.

To all whom it may concern:

Be it known that I, LOUIS J. DEASY, a citizen of the United States, residing at Cincinnati, in the county of Hamilton and State of Ohio, have invented certain new and useful Improvements in Trolley-Poles, of which the following is a specification, reference being had to the accompanying drawings.

This invention relates to new and useful improvements in trolley poles and more particularly to a spring actuated trolley pole, the main object of the present invention being the provision of a trolley pole which is normally retained in an upright position for engagement with the trolley wire and is provided with means whereby should the pole become disengaged from the trolley wire, it will be forced downwardly toward the top of the guard and will thus be entirely out of the way from cross-line wires, over head bridges or the like and is provided with means adapted to be manually operated to return the pole to its normal operative position.

Another object of the present invention is the provision of a device of the above character which will possess advantages in points of efficiency and durability, is inexpensive to manufacture and, at the same time, is simple in construction and operation.

With the above and other objects in view, the invention consists in the novel features of construction, combination and arrangement of parts as will be hereinafter referred to and more particularly pointed out in the specification and claims.

In the accompanying drawings forming a part of this application, Figure 1 is a side elevation of a trolley pole constructed in accordance with my invention, parts thereof being broken away and illustrated in cross section. Fig. 2 is a top plan view. Fig. 3 is a rear end elevation. Fig. 4 is a detail side elevation, illustrating the device in an inoperative position. Fig. 5 is a detail end view illustrating the device in an operative position; and Fig. 6 is a detail longitudinal sectional view of the movable cylinder.

Referring more particularly to the drawings, 1 indicates a trolley guard which may be of any general construction and mounted upon the top thereof, is a plate 2 which is provided with an upwardly projecting annular flange 3 forming a circular bearing socket in which are arranged the ball bear-

ings 4. Extending centrally down through this bearing socket, is a pivot pin 5 which is carried by a movable base member 6. Secured to the lower face of the base member 6, is a bearing plate 7 which is adapted to rest upon the ball bearings 4, whereby to permit of a free rotary movement of the base member 6. Formed upon the one end of the plate 6, is an upright stop member 8 and formed integral with the plate and the member 8, is a cylinder 9. The upper end of the member 8 is bifurcated to form two spaced arms 10, between which is pivotally mounted the body 11. The member 11 forms the main body portion of the trolley pole and projecting outwardly from one end thereof, are the spaced arms 12, between which the pulley 13 is mounted.

Mounted for reciprocation within the cylinder 9, is a movable cylinder 14, in which a coil spring 15 is mounted, one end of said coil spring bearing against the end of the movable cylinder 14 and the other end thereof bears against the movable screw member 16. Thus upon the inward movement of the cylinder 14, the spring 15 will be placed under tension to force the cylinder 14 outwardly, when released. It will be noted that the screw member 16 may be readily adjusted within the cylinder 9 to adjust the tension of the spring. Arranged within the cylinder 9 is a piston rod 17, the inner end of which is connected to the outer end of the movable cylinder 14. The other end of the piston rod is adapted to work within a suitable opening formed in the central portion of the screw member 16 and secured to the outer end of the piston rod by means of the link 18, is a cord 19, which is adapted to be used to reciprocate the cylinder 14 within the cylinder 9. Formed upon the end of the body plate 6, opposite the member 8, is an upwardly projecting post 20, the upper end of which is bifurcated to form two spaced arms 21 and mounted for rotary movement between said arms, is a pulley 22 around which the cord 19 is adapted to pass, before passing over the pulley 13.

Supported by the body member 11, is a trolley pole 23, on the outer end of which is mounted a trolley wheel 24 and mounted between the spaced ears 25, adjacent the outer end of the trolley wheel, is a pulley 26, over which the cord 19 is adapted to pass before being passed downwardly toward the guard. From this it will be apparent that

upon downward pulling movement of the cord 19, the cylinder 14 will be reciprocated within the cylinder 9. Formed integral with the body member 11 and projecting rearwardly therefrom, is a substantially hook-shaped member 27, the inner end of which is provided with a recess 28 and arranged within said recess, is the inner end of a rod 29, upon which the coil spring 30 is mounted. Secured to the outer sides of the ears 10 of the stop plate 9, are the upwardly projecting spaced parallel posts 31, upon the upper ends of which is mounted a plate 32 provided with a central opening through which the upper end of the rod 29 is movable. It will be apparent from this that the coil spring 30 is disposed between the plate 32 and the body of the hook member 27. From this it will be seen that the coil spring 30 will have a tendency to press downwardly upon the hook member 27 and normally retain the trolley pole 23 in a raised position, so that the wheel 24 will normally engage the trolley wire. After the cylinder 14 has been drawn within the cylinder 9, a pivoted latch bar 33 is moved to a horizontal position, the recess 34 in one end thereof engaging with a headed pin 35 to retain the same in its effective position. The latch bar 33, when in its horizontal position, is adapted to engage over the outer end of the cylinder 14, to prevent the same from moving outwardly and forcing the trolley pole 23 downwardly toward the guard and away from the trolley wire. The plate 33 is provided with a tapering projection 36, the inner beveled side 37 of which is adapted to be engaged by the hook 27 upon the downward movement of the same and thus releases the hooked end of the bar from the pin 35 and permits outward sliding movement of the cylinder 14. It will be understood that upon the inward movement of the cylinder, the coil spring 15 is placed under tension, the tension of said spring forcing the cylinder outwardly when released.

In Fig. 4, I have illustrated the device in a normally lowered position and when it is desired to raise the pole 23 to an operative position, so that the trolley wheel 24 will engage the trolley wire, the outer end of the cord 19 is pulled downwardly, thus reciprocating the rod 17 within the cylinder 9 and pulling inwardly upon the cylinder 14, said cylinder being pulled inwardly until the catch member 28 drops downwardly and engages with the headed pin 35, thus retaining the cylinder 14 in its closed position and placing the spring 15 under tension. Should the trolley pole become accidentally detached from the wire, it will spring upwardly by means of the tension of the spring 30, thus the hook member 27 will engage with the tapering portion 37 of the

member 36 and release the catch member 33, allowing the cylinder 14 to reciprocate outwardly by the tension of the spring 15 and in view of the fact that the outer end of the cylinder presses against the hook 27, it will force downwardly upon the trolley pole 23 and return the same to its normal inoperative position. 70

From the above description taken in connection with the accompanying drawings, it will be apparent that I have provided a simple and durable trolley pole which is provided with means whereby the trolley pole is normally retained into engagement with the trolley wire and should the same become released, or disengaged from the trolley wire, it will be automatically forced downwardly toward the top of the car. It will be noted that by having automatic means for returning the trolley pole toward the top of the car, it will eliminate the danger of the pole striking against cross wires, bridges and the like and thus preserve the outer end of the pole. It will also be apparent that my improved device is extremely simple in construction and can be manufactured and placed upon the market at a comparatively low cost. 80 85 90

While I have shown and described the preferred form of my invention, it will be obvious that various changes in the details of construction and in the proportions may be resorted to for successfully carrying my invention into practice, without sacrificing any of the novel features or departing from the scope of the invention, as defined by the appended claims. 95 100 105

Having thus described this invention, what I claim is:—

1. A device of the class described including a movable base, a stationary cylinder carried thereby, a movable cylinder arranged within one end of the stationary cylinder, a piston movable through the stationary cylinder and secured to the movable cylinder, a coil spring arranged within said cylinders and adapted to be placed under tension upon the inward movement of the movable cylinder, a catch adapted to retain said movable cylinder within the stationary cylinder, a pivotally mounted trolley pole carried by the base and normally disposed in a raised position, spring actuated means for retaining said pole in its raised position, and means carried by the pole adapted to engage the catch member upon further upward movement of the pole, whereby to release the movable cylinder, the tension of said spring forcing the cylinder outwardly against the inner end of the pole, whereby to lower the same to an inoperative position. 115 120 125

2. A device of the class described including a movable base member, a trolley wire, a pivoted trolley pole carried by the base, a wheel upon the pole adapted to normally 130

engage the wire, a stationary cylinder carried by the base, a movable cylinder arranged within the stationary cylinder, a coil spring within the cylinders adapted to be placed under tension by the inward movement of the movable cylinder, a catch member adapted to retain said coil spring under tension, a rod supported by the inner end of the pole, a spring upon the rod whereby to retain the pole in a raised position to normally engage the wheel with the wire, and a hook-shaped member carried by the inner end of the pole, whereby to engage the catch

member upon further upward movement of the pole beyond the trolley wire, and release 15 the same, the outward movement of said cylinder engaging the hook member and forcing the trolley pole toward the base, as and for the purpose set forth.

In testimony whereof I hereunto affix my 20 signature in the presence of two witnesses.

LOUIS J. DEASY.
